3 Claims. (Cl. 35—3)

In many ciphering machines there are elements, which will cause certain exchanges of the signs of the plain text. These elements are styled the basic cipher key. These elements present in the arrangement are used in changing sequence. By "period" the number of successive symbols is to be understood, according to which the basic key is again operated in the same succession, or a certain word is rendered by the same ciphers. The technical problem is to render said period as large as possible. According to the invention means are provided to utilize the basic cipher key provided in the machine as perfectly as possible. This is effected in that the elements, which in the basic key correspond with the exchanging alphabet, are used in succession in a sequence, which will closely correspond to the mathematical possibility of their permutations, so that in case n such elements are arranged, the period will approximately be

$$n.(n-1), (n-2) \dots 3, 2, 1$$

Several forms of construction of an arrangement according to the invention are illustrated by way of example in the drawings.

Figure 1 shows a construction of the apparatus of this kind partly in longitudinal section, partly in view.

Figures 2 and 2a show two alphabet cylinders with a part of a corresponding ciphering and deciphering alphabet and the jacket surrounding each cylinder, partly broken away.

Figure 3 shows the alphabet cylinder arrangement with the gear of Figure 1 partly in longitudinal section, partly in view.

Figure 4 represents the same device partly in vertical cross section, partly in view.

Figure 5 shows another modification in which the selection of the switching steps is effected automatically, represented partly in view and partly in longitudinal section.

Figure 6 shows the same arrangement in vertical cross section and partly in view.

Figure 7 shows the same arrangement partly in horizontal section and partly in plan.

Figure 8 shows a detail of Fig. 7 in a perspective view and on an enlarged scale.

Figure 9 shows the same arrangement in section on line IX—IX of Figure 5.

Figure 10 shows a detail of Fig. 9 in a perspective view and on an enlarged scale.

In the modification according to Figures 1 and 4, 1 represents a shaft rotatably journaled in the apparatus, 3 is a cylindrical tube connected with the said shaft, 2 is a cylinder carrying on

its peripheral surface several, for instance 23, exchanging alphabets arranged in an axial direction.

The cylinder 2 is slipped over the inner cylinder 3 and carried along by the latter when rotating, by means of a ball rest 155. 4 represents a mantle or jacket secured to the body of the apparatus. 220 is a footed support attached thereto. 5 is an opening in the said jacket 4, through which the number of the alphabet 10 marked on the cylinder 2 becomes visible. 6 is an opening through which becomes visible the appurtenant alphabet of the cylinder 2. 15 is a ratchet-wheel secured to the shaft 1 and preventing by means of the pawl 16 a retrograde 15 motion of the machine.

The ratchet wheel 14 is likewise secured to the shaft 1 and is engaged by the catch 13, which is connected with the gear-wheel 25 (Figs. 3 and 4). The catch 13 is rotatably disposed on a 20 pin secured in the wheel 25. The gear-wheel 25 is loosely mounted on the shaft 1.

The gear 25 is actuated by way of the gear wheel 151 through the rack 24, which is actuated by the key 11 connected with said rack. The 25 rack 24 is provided with a stop 9 (Figs. 1 and 4), whose motion on the one hand is limited by the bottom portion 7 of the machine and on the other hand by the displaceable slide 8 adapted to be clamped resiliently in notches 120. 223 is 30 an extension of the slide 8 against the bottom of which abuts the stop 9. 224 is a pin on slide 8 adapted to be actuated by finger pressure, the end 227 of which engages in the notches 120.

On the shaft 1 there is furthermore arranged 35 the ratchet-wheel 157 keyed to shaft 1, which is engaged by a pawl 158 which is actuated by the stop 9 of the rack 24 shortly prior to its reaching the lowest position (Figure 4), so that the portion of the machine able to be turned and consisting of the parts 1, 2, 3, 15, 159, 157, 155 is 40 locked and prevented from being moved owing to its inertia beyond the desired position. Pawl 158 is provided with a tooth-shaped end 225 which engages in the locking teeth of ratchet 45 wheel 157 when the rack 24 strikes against the other end 226 of pawl 158. The spring 161 (Fig. 1) serves for raising again the key bar 24. A member 221 is attached to the lower end of spring 161 which member slides in a slotted tube 50 222 and which extends sufficiently far from the tube 222 that it is taken along by the stop 9 which is fixed upon the key bar 24. The machine is operated in the following manner: By turning the cylinder 2 by means of the part 159 55

the desired initial alphabet is caused to become visible within the opening 6. The intended magnitude of the step is adjusted by means of the slide 8. Close to the slot 6 is marked on the 5 mantle 4 the plain alphabet 160. This plain alphabet constitutes the companion element to the code alphabets on the rotary cylinder 2. The first letter of the text is selected in said plain alphabet and replaced by the adjacent exchanging letter. Then, by a single depression of the 10 key 11 and consequently the rack 24 a rotation about a definite arc is effected and a new alphabet is rendered visible in the opening 6, in which the next letter is selected in the same manner. 15 After the selection of one or a plurality of letters the position of the slide 8 is changed. The magnitude of the step is registered each time by the user of the machine in the cipher text which is for instance noted on paper in order to allow 20 subsequent deciphering. This note indicates to the person deciphering which magnitude of steps he must adjust. The number of the notches in which the slide 8 is clamped is preferably one less than the number of alphabets on 25 the cylinder 2 (for instance 22). The change of the magnitude of the step in general is effected after a few letters, for instance five, so that whole words characteristic of the text, are not ciphered by the same length of step. Each 30 change of step represents extra work. On the other hand the ciphering will become the more reliable the more often a change of step is carried out. Although each change of step renders the ciphering more involved, on the other hand, 35 the ciphering becomes more reliable the more often a change of step is executed.

The driving mechanism consisting of a rack 24 and a gear wheel 151 is capable of imparting to the alphabet drum at each step, rotary motions which extend up to a complete revolution 40 equal to 360° . In this way, full utilization of the cipher alphabet is insured, since, at each step, any one of them may follow any other.

In the previously described apparatus, according to Figs. 1 and 4, it was necessary to actuate the 45 lever 8 and adjust it differently for each change of the magnitude of the step. Furthermore, the key 11 had to be depressed for each letter. To combine both operations and to so arrange it that the change in the magnitude of the step is effected also by the motion required per se for each letter, a mechanism is provided in Figs. 3 to 6a, which shows a modified form of construction for the variable step changing and contains 50 further improvements of the invention and which after a few strokes will change the engaging position of the stop 9 of the rack 91 (Figs. 7 and 8). 70 is a crown gear drive advanced one tooth at each stroke. The crown gear drive rotates about pin 200 which is provided with a hub 201. This motion to the extent of one tooth is due to the fact that the edge 71 of the rack 84 (Figs. 6 and 10) catches between two teeth of the crown gear drive 70, so 55 that the edge 71 in engaging with an inclined tooth of the crown drive 70 rotates this crown drive a distance equal to the width of one tooth. The rack 24 with its teeth 199 is in engagement with the gear wheel 87. 72 represents a ball 60 which is forwardly spring-pressed (Figs. 9 and 10) engaging the teeth 73 and fixing the position of the crown drive. 74 are pins, which for instance after five strokes of the rack 84 or alternatively after 5, 3, 2 . . . 5, 3, 2 . . . strokes will 65 advance the gear wheel 150 by one tooth. The 75

gear 150 is secured with a gear wheel 75 (Figs. 6 and 7) of similar design to the same shaft. The pins 74, with the aid of the wheel 150 and of the wheel 76 (Fig. 9), which, for instance, is provided with twelve teeth, turn the drum 77 (Fig. 6), connected with said wheel 76 by means of the spring 78 which is retained in a notch 252 in a disk 253, which in turn is rigidly connected to wheel 76. Thus an adjustment of the drum is rendered possible by a knurled ring 250. The wheel 75 rotates the wheel 79 which has for example thirteen teeth 219, or in any case, a number of teeth which is different from and cannot be divided into equal fractions like the number of teeth of the wheel 76. The wheel 79 transmits its movement to the disk 254 by means of a spring 81. The spring 81 is a short spiral spring, one end of which is fixed to the wheel 79 and the other end to the disk 254. On the disk 254 deepenings 255 are arranged, in which a suitable spring 271 engages (Figs. 6 and 8), which in turn is fixed on the ring 251 of the drum 80. Both drums 80 and 77 are adapted to be adjusted by hand. The drum 80 is adjustable by means of knurled ring 251, and the drum 77 by 250. Both drums 80 and 77 are loosely mounted upon shaft 256. They carry the stops 163, which correspond to the stops formed in Figs. 1 and 4 by the slide 8 and by the bottom portion 7, and form the limiting stops of the stop 9 of the rack 30 91 in Figs. 6 and 7, which correspond to the slide 8. For instance, they are provided with thirteen and twelve rows, respectively, namely, as many rows as the wheels 79 and 76 have teeth. Each row has, for example, seven screw-threaded 35 holes so that one of the drums has 12 times 7 or 84 screw-threaded holes 303 and the other one, 13 times 7 or 91 holes, into which is screwed, in each row, a steel pin 163. The stop 9 can move up and down each time between a pin 163 of the drum 77 and a pin 163 of the drum 80. This stop 9 is in the shape of a capital letter H (Fig. 8). It therefore forms a fork which embraces a pin 163 of the drum 80 and prevents it and consequently the drum 80 from continuing to rotate. the outfit against damage in case of violent depressions of the key lever 85. The key lever 85 is provided with a finger key 214 and is rotatably mounted upon a pin 216 fixed upon the arm 217 attached to the housing. Upon the lever 85 is provided a connecting pin 212 for the lower end of spring 86 while the upper end of the spring 86 is suspended from a pin 211 fixedly attached to the rack 84. The rack 84 engages the gear wheel 87, which is connected to the spring 83. The gear wheel 87 is connected with one end of the spring 90 whose other end is connected with the spring casing 88 firmly united with the gear wheel 89. The spring 90 will admit of the gear wheel 87 continuing to move, even if the wheel 89 is prevented from further motion, when the engaging rack 91 touches, by means of the stop 9, a pin arranged on the drums 77 and 80. The gear wheel 87 keeps on turning to allow the rack 84 to continue on its way to the lowermost point and to move the crown gear drive 70. A spring 92 serves for returning the gear wheel 89. The spring 92 hugs a grooved roll 301 and tends to turn it back and thus the wheel 89. The wheels 87, 89 meshing, respectively, with the racks 84 and 91, are cog wheels, one-half of either one being shown in Fig. 6 (see also Figs. 5 and 7). In order to avoid imperfect strokes owing to negligence which are possible in the form of construction shown in Figures 1 and 4, a lock is provided on the rack 84 consisting of two racks, having oppositely arranged teeth 93 and 94, a double pawl 95, a snapping compression spring 96, which will force said pawl either to the right or to the left side, the stop 97 and the counter-stops 98 and 99, which will reverse the pawl in the highest and lowest position. Then only a complete downward or upward motion is possible each time. 218 is a lever arm which is fixedly attached to the double pawl 95 and against which presses the spring 96. 215 is a locking tooth rigidly attached to the double pawl 295 which engages in the rack 94. In lieu of the safety device 157, 158 shown in Figures 1 and 4 against the swinging beyond a certain point, a positive clutch coupling 100 is arranged, which can be reversed by means of the fork 101 arranged on the lever 102 and the stops 103 and 104, mounted on the rack 84. The clutch 100 comprises two rims having rectangular teeth, one rim being firmly connected with the gear wheel 89 and the other one slidingly connected, in known manner, with the alphabet cylinder 6 so as to cooperate in the rotation thereof, though it can be displaced by the fork 101 to such an extent that it can alternately engage or not engage the other rim. The resilient catch 122 causes the notched wheel 121 having as many notches as there are ciphering alphabets as well as the alphabet part 6 always to be held in proper position. The clutch 100 is always in engagement during the downward movement and always disengaged during the upward movement of the rack 84. 121 is a notched wheel ensuring the accurate adjustment of the portion able to be turned by means of the resilient catch 122.

165 represents a ratchet-wheel, which is firmly connected with the notched wheel 121 and the alphabet part 6 and will prevent a retrograde motion of the rotary portion by means of the pawl 166.

The operation of the device is as follows: Through a few strokes the crown drive is brought into a first position, which is found out

by the ringing of the bell. The position of the drums 77 and 80 can be marked by means of letters in each row of pin holes. By means of the knurled rings 250 and 253 the two drums can be brought into any desired position. The initial position of the two drums is noted in the ciphered text for enabling the deciphering. During each stroke the turning of the parts 121 and 165 with which the alphabet cylinder is connected in the same manner as 2 in Figure 1 with the shaft 1, corresponds to the travel of the stop 9 between a pin 163 of the drum 77 and a pin 163 of the drum 80. As in the examples mentioned the toothed wheel 76 has twelve and the toothed wheel 79 thirteen teeth, the travel of the stop 9 alters in such a manner that it again assumes the same values successively after $12 \times 13 = 156$ changes. If only one drum were present having for example thirteen rows of holes, the travel of the stop 9 would again change in the same manner after every thirteen changes. The drums 77 and 80 are brought into a position indicated, which can be ascertained by means of letters at each row of pin holes. The further operation consists in that, after each letter the key lever 85 is depressed once. The difference of the magnitude of the step for the drum rotation is automatically adjusted by the limiting of the travel of 9 between the pins 163. The notched wheel 121 and the ratchet wheel 165 are in Figures 5 to 9 keyed on a shaft which corresponds to the shaft 1 in Figures 1 and 4. Of the other corresponding parts in Fig. 1, namely 1, 2, 3, 4, 5, 6, 155, 159 and 160 only the parts 4, 5 and 6 are indicated in Fig. 7.

With both constructions deciphering is effected by the introduction of another cylinder, (which does not differ externally from the cylinder 2), carrying alphabets which in the sense explained below correspond to those on the first cylinder. The two cylinders corresponding to the cylinder 2 in Figs. 1 and 4 are designated 2a and 2b in Figs. 2 and 2a, the cylinder 2a serving for ciphering and the other cylinder 2b for deciphering. The first letters of the code alphabet on the cylinder 2a, which is just being used for ciphering, are B F G A C E D. On the deciphering cylinder 2b are found the letters D A E G F B C. In the code alphabet, the letter A is replaced by B and, correspondingly, in the deciphering alphabet the letter B by A. In the code alphabet, the letter B is replaced by F and, correspondingly, in the deciphering alphabet the letter F by B, and so forth. For example, if the word "FACE" is ciphered with the ciphering alphabet assumed in Fig. 2, the symbol "EBGC" will be produced by the designation of the cylinder 2a. In order to decipher "EBGC", the cylinder 2b must be exchanged for the cylinder 2a where "EBGC" corresponds again to "FACE." 209 is one of the code alphabets upon the cylinder 2a corresponding to the code alphabet upon the cylinder 2 in Fig. 3. 210 is one of the deciphering alphabets upon the cylinder 2b. 160 is the plain alphabet upon the jacket or mantle 4. 208 is an enlargement with a knurled hand grip 159a upon the inner cylinder 2a.

In order to be able to easily change the basic key, it is preferably pasted upon the cylinders 2 in the form of series of alphabets printed on paper.

In addition it is of much importance, that the portions able to be turned possess as small an inertia as possible, in order to reduce the impacts of the stop 9 against the pins 163 occurring

during the operation and which extend to the limit of the solidity of the material. For that reason the rotating parts, according to the invention are made of light metal for example aluminium as far as permissible, in particular the cylinders 2 and the attaching body 3.

5 I claim:

1. A ciphering machine having a number of code alphabets, in which the sequence of letters within each code alphabet remains the same during ciphering and deciphering operations, said code alphabets being arranged in rows on the surface of a cylinder, a plain alphabet connected with a stationary part of the machine 10 and a device for rotating said cylinder, said device comprising a gear wheel, a gear having a plurality of teeth adapted to mesh with said wheel, and means for moving said gear to various extents such that the said gear wheel and the cylinder connected therewith are rotated through some of the various angles up to nearly 360°.

15 2. A ciphering machine having a number of code alphabets, in which the sequence of letters within each code alphabet remains the same during ciphering and deciphering operations, said code alphabets being arranged in rows on the surface of a cylinder, a plain alphabet connected with a stationary part of the machine, a

device for rotating said cylinder, said device comprising a gear wheel, a gear having a plurality of teeth adapted to mesh with said wheel, means for moving said gear to various extents such that the said gear wheel and the cylinder connected therewith are rotated through some of the various angles up to nearly 360°, and an adjustable stop for limiting the magnitude of the motion of the said gear. 5

20 3. A ciphering machine having a number of code alphabets, in which the sequence of letters within each code alphabet remains the same during ciphering and deciphering operations, said code alphabets being arranged in rows on the surface of a cylinder, a plain alphabet connected with a stationary part of the machine, a device for rotating said cylinder, said device comprising a gear wheel, a gear having a plurality of teeth adapted to mesh with said wheel, means for moving said gear to various extents 25 such that the said gear wheel and the cylinder connected therewith are rotated through some of the various angles up to nearly 360°, and an adjustable stop for limiting the magnitude of the motion of the said gear, said stop being automatically adjusted after a predetermined number of motions of the said gear. 25

ERNST BRÄUER.
